UNITED STATES PATENT OFFICE.

JOHN SPERRY, OF NEW YORK, N. Y.

IMPROVEMENT IN MANUFACTURING BOXES.

Specification forming part of Letters Patent No. **40,507**, dated November 3, 1863.

To all whom it may concern:

Be it known that I, JOHN SPERRY, of the city, county, and State of New York, have invented a new and useful Improvement in the Manufacture of Boxes; and I do hereby declare that the following is a full, clear, and exact description of the same, reference being had to the accompanying drawings, forming a part of this specification, in which—

Figure 1 represents a perspective view of a box constructed according to my invention. Fig. 2 is a similar view of some of its parts during the process of the construction. Fig. 3 is a transverse vertical section of the same with the cover. Fig. 4 is a modification of the same.

Similar letters of reference in the three views indicate corresponding parts.

The object of this invention is to produce a grain-bound box by combining several thin layers of wood in such a manner that on every part of the box the grain of one layer runs in a different direction to that of the adjacent layer or layers.

The nature of my invention and its advantages will be readily understood from the following description.

A represents a box, which may be square or of any other desired shape or form. When the box is square, its several parts are combined in the following manner: I take two thin pieces of wood, *a b*, Fig. 2, turn the ends *a' b'* up to correspond to the desired height of the box, and place the part *a* over the part *b*, as shown in Fig. 2. The grain of the bottom *b* runs crosswise at right angles to that of the bottom *a*, and the grains of the sides *a' b'* run in a vertical direction. The sides are now strengthened by a band, *c*, placed inside or outside, or two such bands may be used, one inside and the other out. This band is made of one piece of wood cut out to correspond to the inner or outer circumference of the box and to its height, and it is secured to it by glue or other suitable cement. The grain of

band *c* runs at right angles to the grain of the sides *a' b'*, and by these means a splitting of said sides is prevented. The bottom may be further strengthened by an additional layer, *d*, glued to the under surface of the bottom *a*.

When the box is polygonal or round, its construction is slightly varied, according to the number of sides. All the sides may be made out of one piece of wood, *a**, having its ends *a'** turned in toward a common center, and the bottom is completed by securing to said ends one or two layers of wood, and the sides are strengthened by one or two bands glued to their inner or outer circumference, or to both, as previously described. A round box constructed according to this principle is represented in Fig. 4. The bottom is composed of a series of gores, *a**, which are produced by cutting out the bottom edge of the side piece, *a**. After these gores have been turned in, so that their points meet in a common center, they are fastened by one layer of wood, which may be applied inside or outside; or two such layers may be used, one inside and the other outside, and these layers are so placed that their grains run in different directions. The round side wall of the box is strengthened by a band, which may be fastened inside or outside, or two such bands may be applied, one inside and one outside, as previously described.

What I claim as new, and desire to secure by Letters Patent, is—

1. A grain-bound box made of bottom pieces, *a' b'*, and bands *c*, which are so arranged in relation to each other that the grain of one layer crosses the grain of the adjacent layer, substantially as specified.

2. Making the bottom and the sides of a wooden box either partially or wholly out of one and the same piece of material by turning the edges up or in, as set forth.

JOHN SPERRY.
